UNITED STATES PATENT OFFICE.

RICHARD AMES, OF BRIGHTON, ENGLAND.

MACHINE FOR CLEANING, DRYING, HEATING, AND MIXING TARRED MACADAM.

1,041,226.

Specification of Letters Patent.

Patented Oct. 15, 1912.

Application filed August 29, 1911. Serial No. 646,752.

To all whom it may concern:

Be it known that I, RICHARD AMES, a subject of the King of Great Britain, residing at Brighton, in the county of Sussex, 5 England, have invented a new and useful Machine for Cleaning, Drying, Heating, and Mixing Tarred Macadam, of which the following is a specification.

This invention relates to a machine for 10 making tarred macadam from new or old road material, the object of the invention being to enable the machine to deal with existing road material and to convert it into tarred macadam. The machine may be 15 either stationary or portable, the portable form being particularly applicable for converting material which has been removed from the surface of a road by scarifying, into tarred macadam, the operation being 20 conducted on the spot instead of at a depot.

My invention is illustrated by the accompanying drawings in which:—

Figure 1 is longitudinal section of a machine for cleaning, drying, heating and mixing tarred macadam, constructed according 25 to this invention. Fig. 2 is cross section of the same on line A, B, Fig. 1. Fig. 3 is end elevation of the machine. Fig. 4 shows diagrammatic arrangement of flues and heater. 30 The same numerals denote the same parts in all the figures.

Now according to this invention I provide a suitably shaped heating chamber 1, which if the machine is to be portable as 35 shown, is mounted on wheels 2, 3. Within the heating chamber is located a revoluble body which forms the cleaning, drying, heating and mixing apparatus which is constructed as follows:—I provide a metal cylinder or cone 4 which is inserted at each end in a metal plate, 5 being the back plate and 6 the front plate, the said cylinder or cone being secured to the said plates by means of angle irons, or flanging and rivets, 40 in the usual way. Surrounding the cylinder or cone 4 are a number of metal cylinders 8 which are secured at each end to the plates 5 and 6 by means of angle irons, or flanges, and rivets. Each of the cylinders 8 is perforated 45 at 9 on the outer portion of its periphery for a width of about six inches. The cylinders 8 are closed at each end for half

their diameter by the plates 5 and 6. At the feed end of the machine is a feed cone 10 secured to the plate 5 by flanging, or by angle irons, and rivets, the said cone being provided with internal lifters 11 to guide the road material into the cylinders 8. The lifters 11 may be either straight or curved and they may be made of angle irons, the lifters being long enough to extend from the outer end of the cone to the plate 5.

At the driving end of the machine I attach to the plate 5 a metal ring 12 into which the cleaned, dried and heated stone, slag, or other material falls from the cylinders 8. The ring 12 is provided with lifters 13 which carry upward the material to be tarred and deliver it down a chute formed by the partitions 14 and the pyramid 15, into the cylinder or cone 4 where it receives a coating of tar which is pumped into the said cylinder or cone through the pipe 16.

17 is an angle iron ring which serves to 75 retain a certain amount of tar at the end of the cylinder or cone 4 to insure the stone or other material being thoroughly coated with tar.

The superfluous tar falls through the perforated periphery of the ring 12 into a gutter formed by two angle irons 18, 19 and the bottom of the heating chamber, and runs off into a suitable receptacle from whence it is returned to the tar tank.

The revoluble body is supported at the front end of the machine by means of a ring 20 which revolves on antifriction rollers 21 supported by the bracket 22 which is bolted to the frame 23 of the machine.

At the back or driving end of the machine the revoluble body is supported by a hollow shaft 24 which is bolted or riveted to the ring 12. The shaft 24 rotates in a swivel bearing 25 supported by the pedestal 26.

27 is a motor, preferably an oil or petrol engine, the crank shaft of which has keyed thereto a pinion 28 which gears with a spur wheel 29 on the countershaft 30, the counter-shaft being supported in bearings 31 and 32.

A pinion 33 keyed to the countershaft gears with a spur wheel 34 keyed to the hollow shaft 24 so that the revoluble body is rotated direct from a motor carried by the

machine, instead of being driven from a tractor or portable engine.

The exhaust from the motor is preferably discharged into the heating chamber.

5 35 is the water tank for cooling the motor cylinder, 36 and 37 being the usual circulating pipes and 38 the exhaust pipe.

39 is a tank to contain tar or other suitable substance, for example a mixture of tar and oil, hereinafter called compound.

10 40 is a funnel connected to the tank 39, and 41 is a bracket to support a barrel 42 of tar or compound. The tar or compound from the barrel runs down the funnel 40 into the tank 39, from whence it flows into the tar heating apparatus now to be described.

43 is a firebox provided with firebars 44. Surrounding the firebox, 43, is a flue 45, forming three sides of a rectangle, and inside the flue is a boiler 46, the said boiler being rectangular in cross section and forming three sides of a square or rectangle as shown by Figs. 1 and 4. Secured thereto or formed integral with the top and bottom of the tar boiler 46 are vertical ribs 47 the said ribs stopping short of the full length of the sides of the boiler, as shown by Fig. 4. The path of the hot gases from the firebox around the tar boiler is shown by the arrows Fig. 4, the gases escaping from the firebox through apertures 48 into the flues.

A hollow firebrick flue 49 having apertures therein is laid along the floor of the heating chamber 1, the said flue having open ends, and a corresponding flue 50 is provided on the underside of the roof casing below the smoke stack 51 in order to distribute the hot gases uniformly throughout the heating chamber. The hot gases from the firebox after passing around the tar boiler pass by way of the flue 49 into the heating chamber 1, and from thence to the smoke stack 51. The detritus which is screened out by the cylinders 8 falls down the chute 52 into a worm conveyer 53, by means of which it is conveyed to the back of the machine. If the detritus is to be returned into the machine it is raised by a suitable elevator (not shown) and delivered into the dust hopper 54, from whence it falls into the hollow shaft 24 which is provided with a worm 55 which conveys the detritus into the cylinder or cone 4 where it is mixed 55 with the tarred material. Or the screened material may be mixed by hand with the tarred stone as the latter issues from the front end of the cylinder or cone 4.

56 is a rotary pump driven by the motor 60 and which draws the hot tar from the boiler 46 and delivers it through the pipe 16 into the cylinder or cone 4. If desired the pump and pipe 16 may be dispensed with and the gutter used as a tar well which is kept full 65 of hot tar from the heater, the head of tar in

the tank being sufficient to keep the gutter full of tar.

57 is an angle iron ring to prevent stones from becoming wedged between the plate 58 and the revolving feed cone 10.

The cylinder 4 and the cylinders 8 are provided with internal angle iron helices to move the material under treatment along the said cylinders.

The action of the apparatus is as follows:—The material to be treated is fed into the machine through the hopper 59 and falls into the feed cone 10 the lifters in which convey the material into the cylinders 8, which latter by means of their rotation aided by the helices 60 move the material slowly to the opposite end of the machine, the perforated portion of the cylinders 8 screening out the dust, detritus and binding material which falls down the chute 52 into the worm conveyer 53. The material while passing through the cylinders 8 is not only cleaned but is also thoroughly dried and heated ready for being coated with tar. The cleaned, dried and heated material which remains in the cylinders 8 falls into the ring 12 which delivers it into the cylinder or cone 4 where it meets with a jet of tar from the pipe 16, or if the jet of tar is dispensed with, the material is carried by the rotation of the ring 12 through the tar well and is delivered already coated with tar into the cylinder or cone 4. In either case the tarred material is conveyed back to the front of the machine by the internal helix, being turned over and over in its passage, consequently it gets thoroughly coated with tar or compound, the superfluous tar or compound draining off as aforesaid. The fine material screened out by the cylinders 8 is returned to the tarred macadam by means of the conveyer and elevator, or by hand, to form a good binding material thus avoiding spongy roads and the expense of sanding the road after the tarred macadam is laid down. When using new material the binding matrix may be fed into the machine or added by hand to the tarred macadam.

By treating the material on the spot a saving of time and labor is effected as it has been found in practice that hot tarred macadam requires much less rolling down than it does when cold, in addition there is no expense of carting the tarred macadam from a depot to the place where it has to be laid down.

The machine is as far as possible made of boiler plate.

I claim:—

1. In a machine of the class described, 125 the combination with a heating chamber, a revoluble body mounted therein, a feeding device disposed near the forward end of the said revoluble body, a delivery device disposed near the rear end of the revoluble 130

body, means for rotating the body, and means for heating, screening, drying and mixing the material fed.

2. In a machine for cleaning, drying, heating and mixing tarred macadam the combination with a heating chamber of a revoluble body rotating therein consisting of a central cylinder, or cone, a plurality of cylinders disposed in the form of a ring 5 around the central cylinder, or cone, and rotating therewith, a portion of the outer peripheries of the outer cylinders being perforated and the said cylinders being closed for half their diameter at each end, a feed 10 cone fitted with lifters at one end of said cylinders and a ring fitted with lifters at the other end of the cylinders, a chute to convey the cleaned, dried, and heated material into the central cylinder, helices in the 15 cylinders, with means for supporting and for rotating the said cylinders as a whole, means for heating the tar and heating chamber and means for coating the hot macadam with tar all substantially as set forth.
- 25 3. In a machine for cleaning, drying, heating and mixing tarred macadam, the combination of a heating chamber, a revoluble body rotating therein, means for dispensing of the screened out material from 30 said body, means for rotating the revoluble body, means for heating the tar and the heating chamber, and means for forcing the tar from the tar boiler into the central cylinder, or cone, all substantially as set forth.
- 35 4. In a machine of the class described, the combination with a heating chamber, a revoluble body mounted therein, means for feeding material to said revoluble body, means for rotating the revoluble body, and 40 means for heating the heating chamber.
5. In a machine of the class described, the combination with a heating chamber, a revoluble body mounted therein, means for feeding material to said revoluble body, 45 means for rotating said revoluble body, means for heating the heating chamber, and means for coating the material fed into said revoluble body.
6. In a machine of the class described, 50 the combination with a heating chamber, a central cylinder rotating in said chamber, a plurality of cylinders disposed around and rotating with said central cylinder, means for rotating said central cylinder and surrounding cylinders, means for conveying the material into the surrounding cylinders, means located in said cylinders for screening 55 the material as it passes therethrough, and means for carrying off the material screened out by the cylinders.
- 60 7. In a machine of the class described, the combination with a heating chamber, a central cylinder rotating in said chamber, a plurality of cylinders disposed around and 65 rotating with said central cylinder, means

for rotating said central cylinder and surrounding cylinders as a whole, means for conveying the material into the surrounding cylinders, means located in said cylinders for screening the material as it passes therethrough, and means for carrying off the material screened out by the cylinders. 70

8. In a machine of the class described, the combination with a heating chamber, a central cylinder rotating in said chamber, a plurality of cylinders disposed around and rotating with said central cylinder, means for rotating said central cylinder and surrounding cylinders as a whole, means for conveying the material into the surrounding cylinders, means located in said cylinders for screening out the material as it passes therethrough, means for carrying off the material screened out by the cylinders, and means for conveying said screened out material into the central cylinder. 80

9. In a machine of the class described, the combination with a heating chamber, a central cylinder rotating in said chamber, a plurality of cylinders disposed around and rotating with said central cylinder, means for rotating said central cylinder and surrounding cylinders as a whole, means for conveying the material into the surrounding cylinders, means located in said cylinders for screening out the material as it passes therethrough, means for carrying off the material screened out by the cylinders means for conveying said screened out material into the central cylinder, and means for conveying the material remaining in the surrounding cylinders into the central cylinder. 90

10. In a machine of the class described, the combination with a heating chamber, a central cylinder rotating in said chamber, a plurality of cylinders disposed around and rotating with said central cylinder, means for rotating said central cylinder and surrounding cylinders, means for conveying the material into the surrounding cylinders, means located in said cylinders for screening out the material as it passes therethrough, means for carrying off the material screened out by the cylinders, means for conveying said screened out material into the central cylinder, means for conveying the material remaining in the surrounding cylinders into the central cylinder. 100

11. The combination with a heating chamber, central and surrounding cylinders rotating therein, a portion of the outer peripheries of the surrounding cylinders being perforated and the said cylinders being closed for approximately half their diameter at 110 each end, and means for feeding said surrounding cylinders, of means in the surrounding cylinders for moving the material toward the rear end of the machine, means for heating said material as it passes through 115

120 65 130

the said cylinders, means located at the rear end of the cylinders for delivering the heated material into the central cylinder, and means for tarring the material when it reaches the central cylinder.

12. The combination with a heating chamber, central and surrounding cylinders rotating therein, a portion of the outer peripheries of the surrounding cylinders being perforated and the said cylinders being closed for approximately half their diameter at each end, and means for feeding said surrounding cylinders, of means in the surrounding cylinders for moving the material toward the rear end of the machine, means for heating said material as it passes through the said cylinders, means located at the rear end of the cylinders for delivering the heated material into the central cylinder, means for tarring the material when it reaches the central cylinder, and means located in the central cylinder for conveying the tarred material to the front of the machine.

13. The combination with a heating chamber, central and surrounding cylinders rotating therein and means for feeding said surrounding cylinders, of means in the surrounding cylinders for moving the material toward the rear end of the machine, means for screening the material as it passes through the cylinders, means for heating said material as it passes through the cylinders, means located at the rear end of said

cylinders for delivering the heated material into the central cylinder, means for delivering the screened material into the central cylinder, and means for tarring the mixed material when it reaches the central cylinder.

14. In a machine of the character described, the combination with a heating chamber, of a revolvably mounted body therein, means for rotating said body, a tar tank, a tar heating means in communication with said tank, hollow apertured flues provided with open ends and secured to the floor and roof of the heating chamber thereby providing means for uniformly heating the heating chamber, and means for delivering the heated tar into the revolvble body.

15. In a machine of the character described, the combination with a heating chamber, of a revolvably mounted body therein, means for rotating said body, a tar tank, a tar heating means in communication with said tank, hollow apertured flues provided with open ends and secured to the floor and roof of the heating chamber thereby providing means for uniformly heating the heating chamber, means for delivering the heated tar into the revolvble body, and means for mixing the heated tar with the material to be tarred when they are brought together in the revolvble body.

RICHARD AMES.
